UNITED STATES PATENT OFFICE.

EDWIN H. BENNETT, OF BAYONNE, NEW JERSEY, ASSIGNOR TO GEORGE H. BABCOCK AND STEPHEN WILCOX, OF NEW YORK, N. Y.

TUBE-FASTENING.

SPECIFICATION forming part of Letters Patent No. 235,406, dated December 14, 1880.

Application filed October 29, 1879.

To all whom it may concern:

Be it known that I, EDWIN H. BENNETT, of Bayonne, Hudson county, and State of New Jersey, have invented certain new and useful Improvements relating to Tube-Fastenings; and I do hereby declare that the following is a full and exact description thereof.

The invention is adapted for securing the tubes of steam-boilers and analogous structures requiring a tight fastening, adapted to endure high temperatures and great strains. It is intended more particularly for the style of boilers set forth in the several patents to Babcock and Wilcox, having the water inclosed in tubes, and small end chambers of cast-iron suitably connected together to form a single boiler of a great number of sections. I have discovered that the holes for the tubes may be produced in the act of casting in common green sand. I make the holes tapering. The taper facilitates the drawing of the pattern, and also contributes materially to the perfection of the fastening. The strain on this kind of boiler, and in other places similarly conditioned, is in the direction to force the end connection away from the tube. The hole is tapered, so that the outer end is the largest. I employ an expanding-tool, adapted to give the same taper to the tube end and force the metal of the tube into the corresponding conical form, applying only sufficient force to slightly imprint the casting into the outer surface of the expanded tube.

The strain on the connection is always forcing the tapered surfaces into a closer connection. A tight joint results with little distortion of the metal of the tube.

My invention allows tubes to serve successfully which possess a less degree of ductility than is required for the ordinary modes of setting.

The accompanying drawings form a part of this specification, and represent what I consider the best means of carrying out the invention.

Figure 1 is a central longitudinal section through one of the tube ends and the adjacent parts in the act of being expanded. Fig. 2 is an end view of the same with a cross-section through the body of the tube. Fig. 3 is an elevation, partly in section, showing a number of the connections on a smaller scale.

Similar letters of reference indicate like parts in all the figures.

A is the body of the tube, and A' a conical end formed thereon. B is the main body of an end casting, and b the tapering hole formed therein to receive the tube.

M, &c., are the rollers of the expander. They are caged in a ring, N, and are forced apart by a tapering mandrel, P, which is turned by a crank or otherwise, and is forced axially, as required, to present a larger diameter within the rollers, and thus to force the rollers M outward and effect the expansion.

The hole b in the casting may be finished with a tool, to give a more exactly mathematical form; but I do not consider such necessary. I esteem it an important advantage of the invention that the holes may be produced with perfection by the ordinary process of casting, and require no tooling.

The rollers M may be tapered in the same direction and to the same degree as the mandrel. In other words, the proper degree of taper for the hole being determined, it may be divided between the mandrel and the rollers. This allows the rollers and mandrel to roll together with no sliding and with mathematical precision; but I do not esteem this feature essential to success. The rollers may be made absolutely cylindrical or tapered in the opposite direction, the mandrel being suitably tapered with each to induce the required degree of taper in the interior, and consequently of the exterior of the tube ends A'.

I prefer to expand the tubes only to such extent as to slightly imprint the casting B into the outer tapering surface of the tube end A'. The bearing-surface is made narrow to facilitate such imprinting.

I claim as my invention—

A steam-boiler having castings B, provided with tapering holes b flaring outwardly, in combination with tubes A, having correspondingly-tapered ends A', combined and adapted to serve as and for the purposes herein specified.

In testimony whereof I have hereunto set my hand, this 20th day of October, 1879, in the presence of two subscribing witnesses.

Witnesses: E. H. BENNETT.
